UNITED STATES PATENT OFFICE.

LESLIE GRISCOM, OF PHILADELPHIA, PENNSYLVANIA, ASSIGNOR TO FLETCHER WORKS, INCORPORATED, A CORPORATION OF PENNSYLVANIA.

BEARING FOR CENTRIFUGAL MACHINES.

1,305,796.

Specification of Letters Patent. Patented June 3, 1919.

Application filed April 13, 1916. Serial No. 90,822.

To all whom it may concern:

Be it known that I, LESLIE GRISCOM, a citizen of the United States, and resident of Philadelphia, county of Philadelphia, and 5 State of Pennsylvania, have invented new and useful Improvements in Bearings for Centrifugal Machines, of which the following is a specification.

The invention relates to improvements in 10 centrifugal machines, such as are used for extracting liquids from solid substances.

Machines of this type comprise a frame upon which a curb or tub is carried and within which curb or tub there revolves a basket which is carried on a shaft that is supported in a standard carried on the frame. When in use this basket revolves at 15 a high rate of speed and hence it is advisable to have this standard mounted so 20 that the upper end thereof can yield or swing in order to accommodate itself to the vibratory movements which frequently take place during the time that the basket is being spun or revolved at the high velocities 25 employed.

The present invention relates to the manner of mounting and securing this standard in place on the frame; it also relates to the manner of mounting the shaft in the standard 30 which carries the basket, as well as to the means whereby the shaft is driven. Frequently, in centrifugal machines it is desirable to discharge the solid matter from the basket through openings in the bottom 35 thereof.

According to the construction shown in the accompanying drawings which constitute a part of the specification, these openings are normally closed by a bell-shaped 40 valve that is located within and which engages the upper surface of a bottom portion of the basket. This valve is preferably made so that it can be secured in closing position by bayonet connection between it and the 45 shaft carrying the basket. From the discharge openings through the bottom of the basket the solid matters pass to an inclined trough whereby they are conveyed from the machine. At the upper end of the trough 50 there is a circular opening through which the standard passes and in order that the solid substance being discharged from the basket will not pass through this opening there is provided around the shaft—that is 55 located within the standard—a bell-shaped

portion. This bell-shaped portion covers the circular opening at the upper end of the trough and is arranged to direct any substance passing through the bottom of the basket into the trough. This bell-shaped 60 portion may be considered to be and is a part of the basket and the discharge openings from the basket are located on the exterior of this bell-shaped portion. Means for securing the upright hollow member or 65 standard in place relative to the frame comprises bolts and buffer springs all of which are located below and none of which extend through the trough. It will therefore be seen that the arrangement is such that there 70 is little liability or chance for a clogging of the trough by the solid matters discharged through the openings in the bottom of the basket and that there is also practically no chance for any of the liquid or solid matters, which are acted upon in the machine coming in contact with the bearings for the 75 shaft, or with the means that operate the shaft.

In the apparatus illustrated the bearings 80 are of the type known as anti-friction bearings, that is, they are ball-bearings, and the construction is such that these bearings will at all times be properly oiled. The machine is also preferably constructed so that all 85 parts thereof are readily accessible to facilitate adjustment or repair.

A specific embodiment of the invention is illustrated in said accompanying drawings, in which drawings— 90

Figure 1 is a vertical sectional view through the central portion of the machine. This is a view taken as on the plane 1—1 looking in the direction of the arrows.

Fig. 2 is a vertical view looking at the 95 machine from the rear; in other words, in the direction of the arrow 2 shown in Fig. 1, and Fig. 3 is a drawing of a detail.

The machine comprises a main frame 1 that is seated on any suitable foundation. 100 A curb or tub 2 is carried on the upper portion of this frame and is secured in place thereupon as by means of bolts 3. A revolvable basket 4 is located within the curb or tub. The basket is mounted upon the 105 upper end of a shaft 5 that extends through and is carried by an upright hollow member or standard 6. The standard is in turn mounted upon a bracket 7 which in effect constitutes a part of the main frame since 110

2

it is secured thereto in a rigid manner by means of the bolts 8. The standard 6 is provided at its lower end with a spherical portion 9 that rests in a spherical seat in the bracket 7. The standard is maintained in an upright position by buffering members, six in number, which are equally spaced about the standard. Each of these buffering members comprises a bolt 12, the head 12' of which rests in a semispherical member 13, that is in turn seated in an ear 14 on the bracket 7; the bolt also passes through an ear 15 on the standard 6. On the upper end of each of these bolts there is a cap 16 between which and the ears 15 of the standard there is located and secured in compression a spring 17. These springs are inclined to the horizontal and are tangent to a sphere the center of which coincides with the center of the spherical seat. It will thus be manifest that the upper end of the standard will have a slight yielding movement which is permitted to take place due to the ball and socket bearing at the lower end of the standard 6 and the six buffering members just described. The several buffering members are comparatively powerful but they are opposed to each other and thus tend to neutralize each other whereby when the basket is being revolved the standard for the shaft carrying the basket can accommodate itself to any unevenly balanced load thus relieving undue strains on the bearings and avoiding objectionable vibration. The driving of the shaft is effected by means of a pulley 18 which is connected to the shaft at the lower end thereof; preferably integral with this pulley there is a brake-member 19 which can be utilized to arrest, when desired, the movement of the revoluble element which comprises the shaft and the basket. The pulley 18 is positioned so that the pressure of the belt which passes over the pulley is in line with the center of the spherical seat. With the parts arranged as shown the machine can be constructed so as to be driven by a belt which comes in from any one of three directions, viz., from the right, the left or the back, the belt being prevented by the trough from coming in from the fourth direction, viz., from the front.

The frame is provided at the upper part thereof with a gutter portion 20 in which there is located a gutter lining 21. This gutter lining is arranged so as to receive any of the liquids dropped into it from the space 22 between the curb or tub and the revoluble basket. This gutter lining emp ties into a conduit 23 that conveys the liquids from the machine. The basket 4 comprises the usual perforated cylindrical member 24 that is carried by a bottom member 25, the latter of which is fixedly secured to the shaft 5 by being clamped between

a shoulder S and nut N. A key K is provided between the shaft 5 and member 25 so that both will rotate together. In order to lock the nut N in place a pin may be provided if desired. The bottom 25 has an inwardly and downwardly sloping portion 26, which sloping portion is in effect an annular portion that provides substantially the entire floor part of the basket. This bottom member 25 also comprises a bell 27 and webs 28 that serve to connect the annular portion 26 to the bell portion 27. Between these webs there are openings that serve as discharge openings whereby solid materials in the basket can slide down the annular portion 26, when permitted to do so, from the basket.

The main frame 1 has a trough 29 arranged to receive the material discharged from the basket through the discharge openings just referred to. The upper end 30 of the trough is circular in shape and through the opening 31 the standard 6 passes.

It will be observed that the bell 27 is larger at the lower end than the upper portion 30 of the trough whereby any material passing from the basket will be prevented from entering the space between the upper portion 30 of the trough and the standard 6. There is located within the basket a valve 32 which engages the lower end of the inwardly and downwardly sloping portion 26 so as to close or cover the opening in the basket when the valve 32 is in place. When the valve is raised, as will be presently explained, the material within the basket can be discharged in the manner heretofore described. This valve 32 preferably comprises a bell-shaped member 33 to the lower end of which there is secured a rubber packing 34. This packing may be secured in place as by clamping it between the inner ring 35 and the lower end 36 of the bell-shaped member 33. To the upper end of the bell-shaped member 33 there is secured a hollow stem-member 37. Within this stem-member 37 there is located the lower end of an upper bayonet-connecting member 38. This bayonet-connecting member 38 cooperates with a lower bayonet-connecting member 39, the latter of which is secured at 40 to the upper end of the shaft 5 and is locked or keyed in place on said shaft as by means of a pin 41. The upper bayonet-connecting member 38 passes upwardly through the upper end of the hollow member 37 into a nut 42. A lock-nut 43 is provided and over the nuts 42 and 43 there is passed the threaded portion 44 of the handle member 45. This handle member 45 has a flange 46 which extends over and below the top edge of the hollow stem-member 37. The handle member 45, the nut 42 and the upper bayonet member 38 are all secured together so that when a partial rotation is imparted

to the handle member 45 a corresponding partial rotation will be imparted to the upper bayonet member 38. It will thus be noted that when the shaft 5 is still the bayonet connection can be made or disengaged at the will of the operator by merely turning the handle member 45. When the members of the bayonet connection are in disengaged position the valve 32 can be readily raised 10 and removed from the curb or tub, if desired, by merely lifting on the handle member 45; whereas, on the other hand, the valve 32 will be maintained in closed position or in position to cover the holes by completing 15 the bayonet connection. Any suitable packing may be provided at 47 between the nut 42 and the upper end of the hollow stem-member 37.

In case it should be desired to remove the 20 basket 4 from the shaft 5 it will be observed that it will only be necessary to disconnect the bayonet connection and remove the valve 32; then remove the nut N—and if desired possibly the lower bayonet-connecting member 25 39 from the shaft 5—and then remove the basket proper as a whole from its place on the shaft. The shaft 5 is mounted in the upright standard 6 in the following manner:

An intermediate member or bearing ring 30 carrier 48 is forced on the shaft so as to engage the underside of the shoulder S. On the exterior of this bearing-ring carrier there is mounted an inner ring 49 of a radial roller bearing 50. The underside of the bearing-ring carrier rests upon an upper ring 51 of a roller thrust bearing 52. The outer ring 53 of the radial/roller bearing 50 is located within a socket portion at the upper end of the upright hollow member or standard 35 6 and engages with the latter. It will thus be observed that the radial thrust from the shaft is imparted to the upper end of the standard through the bearing 50 just referred to. The downward thrust of the 40 shaft is taken care of by means of the thrust bearing 52 the lower bearing ring 54 of which rests upon a ring 55 that is seated in a socket in the standard 6. Sufficient space is provided between the shaft 5 on the one hand and the lower portion of the intermediate bearing-ring carrier 48 and thrust bearing 52 on the other hand to permit the reception of a cylindrical sleeve 56. This sleeve 56 is fixedly secured in the standard 55 6, as by means of a screw connection at 57. It will be observed that the upper end of this sleeve 57 extends beyond the center of the balls in the radial roller bearing 50 whereby when oil is forced into the standard 6, as by 60 removing the plug p and forcing the oil through the check-valve v and the duct 58, it will be caused to properly oil not only the thrust bearing 52 but also the radial bearing 50, prior to escaping from the space 65 containing these bearings, by flowing over

the upper end of the sleeve 56. By removing the plug p' the operator can tell when the bearings 50 and 52 have been sufficiently supplied with oil.

A vent hole or duct 59 is provided in the 70 intermediate or bearing-ring carrier 48 to break any vacuum that may be created by the oil flowing downwardly between the retaining sleeve 56 and the shaft. If it were not for the breaking of this vacuum the oil 75 would at times siphon out of the upper bearing to a place which is on a level with the lower face of the upper raceway of the thrust bearing 51. The upper end of the standard 6 is provided with a cap 60 that 80 is secured in place by cap-screws 61, and any suitable packing can be provided, as at 62', between the cap 60 and the intermediate or upper ring carrier 48 on the shaft 5. As this bearing ring carrier is practically fixed 85 upon the shaft it may be considered to constitute a part of the shaft. Any oil which flows over the upper edge of the cylindrical sleeve 56 is free to pass downwardly in the space between the shaft 5 and the standard 90 6 to the radial-roller bearing 62. The inner ring 63 of this bearing is seated on a depending stem 64 and bears against a shoulder 65. The inner ring 63 is locked in place, as by 95 means of a lock-nut 66, the latter of which can be locked on the lower end of the standard, as by means of a pin or other securing means. The outer ring 67 of the radial-roller bearing 62 is seated on a member 68. This member 68 in effect constitutes the hub 100 portion of the driving pulley 18 and brake-member 19. This hub portion is maintained in place on the lower end of the shaft 5 by means of a nut 69 and key 70.

In order to prevent any leakage of oil 105 from between the shaft and this hub portion a cap 71 is provided. The oil passing downward along the shaft 5 can pass into the space below the radial bearing 62, as by flowing through the opening at 72. Since 110 there is no opening for the escape of oil below this bearing it will back up, covering the bearing in the receiving space 73, from whence it can flow through drain openings 74.

From what has preceded it will be manifest that all the bearings are arranged so as to be constantly flooded with oil, thus insuring proper lubrication. The basket and shaft can be readily removed by merely removing the cap 71, the nut 69 and the hub 68, after which the basket and shaft can be lifted from the machine.

It will be manifest that the curb top X would have to be removed in case it should be desired to lift the basket from the curb or tub when the latter is in place on the frame. It will also be manifest from what has preceded that all of the operative parts of the machine, for instance the bearings, 125 130

the driving mechanism, and the buffing members are protected from contact with any of the substances being operated upon in the machine, be it the solid matter or the liquids. The buffer members for instance are arranged below the trough and do not pass through the trough; hence they will remain clean and are always accessible, as through the opening O in the rear of the machine. The driving mechanism and the brake mechanism are accessible from below the machine and as previously indicated all of the wearing parts are made of ball bearings and are well lubricated whereby comparatively little power will be consumed and whereby they will require little attention.

It will be manifest that a roller bearing is the equivalent of a ball bearing and that the latter term should be broadly construed. It will furthermore be noted that according to certain phases of the invention a plain bearing could be used in place of the more expensive but more efficient ball bearing if for any reason it became desirable to employ the former type of bearings.

It will also be noted that by removing the nut N from the shaft and by removing the bolts 8 that secure the bracket in place the entire mechanism comprising the shaft, standard, bearing, springs, brackets, etc., can be lowered as a whole for repairs, and if a separate similar mechanism were on hand a replacement could be quickly made and the operation of the machine delayed but little. If this feature of construction is to be taken advantage of it will be manifest that the foundation or supports for the machine should be such that the parts will be accessible from below—a foundation construction which can be readily made.

The materials of which the machine is made are of course dependent upon the use to which the machine is put. In the particular machine illustrated a lining 75, such as lead, is provided on the interior of the curb or tub. The gutter lining is made of bronze, as is also the revoluble basket. A suitable packing as 76 is also provided between the gutter lining and the lower end of the curb or tub.

The improvements herein set forth are not limited to the precise construction and arrangement shown and described for they may be embodied in various forms and modifications without departing from the spirit and scope of the invention.

What I claim is:

1. A centrifugal machine comprising in combination a basket, a hollow upright member or standard, a shaft carried in said standard, upon which shaft said basket is mounted, a radial roller bearing between the shaft and the upper end of the standard, a thrust bearing between the shaft and said standard, and a radial roller bearing be-

tween the exterior of said standard and a member which is on or secured to the shaft.

2. In combination, a hollow member, a shaft in said hollow member, a cylindrical drum on said shaft, a radial roller bearing between the interior of said drum and the exterior of the hollow member, a thrust bearing between the shaft and said hollow member, and a second radial roller bearing between the interior of said hollow member and a member that is on or secured to the shaft.

3. A centrifugal machine comprising in combination a basket, a hollow upright member or standard which extends into or adjacent to the space defined by the lower portion of the basket, a shaft carried in said standard and upon which shaft said basket is mounted, a radial roller bearing between the shaft and the upper end of the standard, a thrust bearing between the shaft and said standard, and a radial roller bearing between the exterior of said standard and a member which is on or secured to the lower end of said shaft.

4. A centrifugal machine comprising in combination a hollow member or standard, a basket with a bottom having a bell-shaped central portion into the hollow under portion of which the upper end of said standard projects, a shaft to which said bell-shaped portion of the bottom is connected, which shaft extends from the upper end of said standard, said shaft having thereupon a shoulder against the underside of which a bearing ring carrier engages, a roller radial bearing the inner ring of which is mounted upon said carrier and the outer ring of which is seated within a recess at the upper end of the standard, a roller thrust bearing upon the upper ring of which said carrier ring is seated, the lower ring of said thrust bearing being carried in a seat on said standard, the standard having a cylindrical sleeve which extends through a space between the thrust bearing members and the shaft up into a space between the bearing ring carrier and the shaft, said cylindrical sleeve extending upwardly past the center of the balls or rollers in said roller radial bearing, there also being means whereby oil can be supplied to the spaces in which said bearings are located.

5. A centrifugal machine comprising in combination a main frame, a standard, said standard having a spherical portion which is seated in the socket of a bracket on the frame, means for maintaining the standard in upright position on the frame, a basket, a shaft extending through the standard to which shaft the basket is secured, a radial roller bearing located at the upper end of the standard between the standard and the shaft, a radial roller bearing below the spherical portion of the standard between

- the standard and the shaft, and a thrust bearing located below the upper radial roller bearing, which thrust bearing is between the shaft and the standard, the standard being 5 provided with a cylindrical sleeve which extends upwardly through a space between the thrust bearing and the shaft into a space between the upper radial bearing and the shaft to a place above the plane passing 10 through the centers of the rollers or balls in said upper radial bearing, there being a duct through which oil can flow to said thrust bearing and upper radial bearing.
6. A machine comprising in combination 15 a hollow standard or upright member having a spherical seat at the lower end thereof, a bracket member providing a seat for receiving said spherical end, and buffer means for maintaining the standard in upright position, a shaft located in said standard, means for driving said shaft, and a roller bearing, the inner ring of which bearing is seated on the exterior of said standard below said spherical portion thereof, the outer ring of 20 which bearing is seated on a hub member carried on said shaft.
7. A machine comprising in combination 25 a hollow standard or upright member, a shaft located in said standard, means for driving said shaft, and a roller bearing, the inner ring of which bearing is seated on the exterior of said standard, the outer ring of which bearing is seated on a hub member carried on the lower end portion of said 30 shaft, said hub member being provided with a cap covering the lower end of said shaft, the construction being such that oil flowing downwardly along said shaft will be permitted to enter the spaces in which said 35 bearing is located.
8. A centrifugal machine comprising in combination a main frame, a hollow standard, a bracket carried by said frame for supporting said standard, a curb or tub carried by said frame, a shaft extending through 40 said standard and a basket mounted upon said shaft, the lower end of said standard being in the form of a portion of a sphere and being mounted in a spherical seat in 45 said bracket so that the upper end of the standard can yield and swing in any direction, there being a bearing in the upper end of said standard between it and the shaft, there also being yieldable means extending 50 between the bracket and the lower portion of the standard for maintaining the standard in upright position, which yieldable means comprises springs that are inclined to the horizontal and that are tangential 55 to a sphere the center of which coincides with the center of the spherical seat of the bracket.
9. A centrifugal machine of the class described comprising in combination a main frame, a hollow upright member or stand- 60 ard, a bracket for supporting the standard on the frame the lower end of said standard being a portion of a sphere which is seated in a spherical portion or seat on the bracket, inclined bolts extending from the bracket 65 upwardly through ears or lips on the standard, there also being compression springs between the upper end of the bolt and said lips whereby said bolt and spring construction will serve as buffer means for yieldably holding the standard in upright position, a curb or tub on the frame, a shaft extending through the standard, driving means secured to the lower end of the shaft, a basket secured to the upper end of the shaft, a 70 radial ball bearing between the shaft and the upper end of the upright standard, a thrust ball bearing arranged to receive the downward thrust of the vertical load upon the shaft, and a radial ball bearing below 75 said spherical seat between the hollow standard and a member connected to the shaft.
10. A centrifugal machine having in combination with the main portion of the frame and the revoluble basket which extends over 80 the frame, of a bracket, a standard yieldably mounted upon said bracket, a driving shaft for said basket mounted in said standard, and a shaft driving member connected with said shaft, which bracket, standard, shaft 85 and shaft driving member can be lowered from place and removed from the machine by disconnecting the revoluble basket from the shaft and by disconnecting the bracket from the main portion of the frame. 90
11. A machine of the class described having in combination an upright hollow standard, a shaft mounted so as to revolve in said standard and a suitable bearing between the upper end of the standard and said shaft, 95 the standard being provided with a duct or passageway and a check-valve for closing said passageway through which valve and passageway lubricating oil can be supplied to said bearing, the standard also being provided with a removable plug whereby the shaft on the interior of the standard can be viewed to determine when sufficient lubricating oil has been supplied to said bearing. 100
12. A machine of the class described having in combination a bracket, an upright standard mounted upon and secured to said bracket, there being a ball and socket bearing between said standard and said bracket, a basket driving shaft extending from the 105 lower end of said standard and a member secured to the lower end of said shaft between which member and the lower exterior end of the standard there is provided a bearing suitable to absorb radial thrust. 115
13. A machine of the class described having in combination a bracket, an upright standard mounted upon and secured to said bracket, there being a ball and socket bearing between said standard and said bracket, 120
14. A machine of the class described having in combination a bracket, an upright standard mounted upon and secured to said bracket, there being a ball and socket bearing between said standard and said bracket, 125
15. A machine of the class described having in combination a bracket, an upright standard mounted upon and secured to said bracket, there being a ball and socket bearing between said standard and said bracket, 130

6
a shaft extending through said standard, a basket carried at the upper end of the shaft and a member secured to the lower end of said shaft between which member and the 5 exterior portion of the lower end of the standard there is provided a suitable radial bearing, said member also carrying a pulley which is positioned so that the pressure of

the belt which passes over the pulley is in line with the center of the spherical seat. 10

This specification signed and witnessed this 6th day of April, A. D., 1916.
